UNITED STATES PATENT OFFICE.

MICHAEL LESKIEWICZ AND WOJCIECH BARTKOWIAK, OF CHICAGO, ILLINOIS.

DESIGN FOR A COMBINED PICTURE FRAME AND STAND THEREFOR.

Application filed February 17, 1926. Serial No. 16,562. Term of patent 14 years.

To all whom it may concern:

Be it known that we, (1) MICHAEL LESKIEWICZ and (2) WOJCIECH BARTKOWIAK, citizens of (1) Poland and (2) the United States of America, respectively, residing at Chicago, in the county of Cook and State of Illinois, have invented a new, original, and ornamental Design for Combined Picture Frames and Stands Therefor, of which the following is a specification, reference being had to the accompanying drawing, forming part thereof.

Fig. 1 is a front elevational view, and Fig. 2 is a side elevational view of a combined picture frame and stand therefor, showing our new design.

We claim:

The ornamental design for a combined picture frame and stand therefor, as shown.

MICHAEL LESKIEWICZ.
WOJCIECH BARTKOWIAK.
